METHOD AND APPARATUS FOR VACUUM
COATING METALLIC SUBSTRATES

Philip J. Clough, Reading, Mass., assignor to National Research Corporation, Cambridge, Mass., a corporation of Massachusetts

Filed Aug. 13, 1958, Ser. No. 754,830
4 Claims. (Cl. 117—107)

This invention relates to coating and more particularly to high vacuum coating of a substrate, such as black iron plate, with a metal, such as aluminum. For convenience, the invention will be initially described in its use for the preparation of aluminum coated black iron which can serve as a substitute for "tin plate." In the coating of black plate with aluminum, it is highly desirable that the aluminum be deposited continuously on a black iron strip which is moved from the atmosphere through several stages of decreased pressure, through a coating chamber where a thin, shiny aluminum coating is applied by vaporizing the aluminum and condensing the aluminum on the black iron and then removing the strip through another series of seals back out to the atmosphere.

The present invention is particularly concerned with the problem of moving the substrate to the atmosphere after coating. In the past, many suggestions have been made for moving substrates into and out of a high vacuum coating chamber. Some of these suggestions have involved the use of a barometric leg for permitting passage of the substrate through a wide pressure differential without permitting atmospheric air to leak into the coating chamber. The present invention is particularly directed to an improved barometric leg construction which employs all of the advantages of previous barometric legs and additionally provides for positive maintenance of a high vacuum in the coating chamber which is free of vapors of the liquid forming the barometric leg.

Another object of the invention is to provide a high vacuum coating apparatus of the above type which can employ large clearances in the outlet seal so that the freshly-deposited aluminum coating will not be subject to scratching or abrasion.

Another object of the invention is to provide a coating apparatus wherein the outlet seal is made with sufficiently large clearances so that irregularities in the steel, such as tears, welds and the like can be passed through the equipment without danger of jamming or tearing the sheet.

Other objects of the invention will in part be obvious and will in part appear hereinafter.

The drawing is a diagrammatic, schematic, sectional view of one preferred embodiment of the invention.

In the present invention the substrate to be coated is first cleaned and then passed into a coating chamber through several stages of decreasing pressure where the residual cleaning fluid (e.g. water) is evaporated and the substrate is preferably preheated to a temperature on the order of 400° F. Thereafter the substrate passes through a coating chamber which is maintained at a high vacuum on the order of 1 micron Hg abs. where the substrate is exposed to a stream of aluminum vapors which condenses on the substrate to form a shiny, adherent coating. The substrate then passes through a seal of rather wide clearance into a trap chamber which is preferably maintained at a pressure somewhat less than the pressure in the coat-

2

ing chamber so that there is a slight flow of gases from the coating chamber into the trap chamber. In one preferred embodiment of the invention, the trap chamber is maintained at a pressure of about .15 micron Hg abs. Thus some gas will continuously flow from the coating chamber to the trap chamber through the seal between these two chambers. In the trap chamber, the hot substrate passes into a barometric leg which isolates the trap chamber from the next succeeding chamber.

10 The liquid of the barometric seal is preferably a low vapor pressure oil such as a vacuum pump oil. Since the substrate is hot as it enters the oil, it will tend to vaporize some of the oil and also raise the temperature of the oil bath. Since these oil vapors would raise the total pressure in the trap chamber, it is necessary to condense these vapors. Accordingly the lower portion of the trap chamber adjacent the surface of the barometric leg is provided with a cooling means, such as a cooling coil for condensing the vapors leaving the oil surface. A cooling coil is 15 also preferably provided in the oil for maintaining the oil in the barometric leg at a predetermined low temperature to prevent undue heating thereof due to transfer of heat from the substrate to the oil.

Since it is desirable to maintain the trap chamber at an 20 absolute pressure less than the pressure in the coating chamber, sufficient cooling surface is provided in the trap chamber to condense substantially all of the vapors emanating from the surface of oil in the barometric leg. Accordingly, the pressure of oil vapor in the trap chamber is 25 maintained much less than the total pressure in the coating chamber. Any residual vapors of oil in the trap chamber are prevented from diffusing into the coating chamber due to the fact that there is a countercurrent flow of gas from the coating chamber into the trap chamber 30 through the seal connecting these two passages. In order to provide this countercurrent flow, one preferred embodiment of the invention has the high vacuum pump for evacuating the coating chamber connected to the trap chamber. Accordingly, the coating chamber is evacuated 35 through the trap chamber thus inherently producing a lower pressure in the trap chamber than in the coating chamber.

In order to more fully understand the invention, reference should be had to the drawing, which is a diagrammatic, schematic representation of one preferred embodiment of the invention. In this drawing, the substrate is indicated at 10, the substrate being guided through a coating chamber 12 where it is exposed to aluminum vapors from a coating source generally indicated at 14. As the 40 substrate enters the coating apparatus, it passes from the atmosphere through sequentially arranged chambers 16, 18 and 20 of decreasing pressure. These chambers are separated from the atmosphere and each other by seals 22, 24, 26 and 28, these seals being diagrammatically 45 illustrated as close fitting rolls with surfaces driven at the same speed as the speed of travel of the substrate. Obviously, many other types of seals can be employed, including barometric legs and the like. In the chamber 20 immediately preceding the coating chamber, the substrate is 50 preferably heated by means of a heating element schematically indicated at 29 which may be an induction coil and thereafter passes over the source 14 of aluminum vapors. This source preferably comprises a crucible 30 which is heated by an induction coil 32. The freshly

coated sheet then passes through a fairly large opening 34 which has a sufficiently large gap so as to prevent the possibility of scratching the freshly formed aluminum coating. From the passage 34 the substrate travels into the trap chamber 36 which is maintained at a pressure lower than in the coating chamber 12. In the trap chamber, the substrate passes over roll 38 and then down through a barometric leg 40, over a plurality of other rolls 42 and out of the coating apparatus through an intermediate pressure chamber 44 and a second barometric leg 46.

A cooling coil 50 is illustrated in the trap chamber 36 above the surface of the liquid 40 forming the barometric leg. As mentioned previously, this cooling coil condenses all vapors generated when the hot substrate contacts the oil 40. It is also preferred that a portion of this cooling coil be in contact with the main body of the liquid so as to keep the liquid 40 cool and prevent the heating thereof by the passage of the hot substrate into the liquid. Due to the excellent heat transfer between the oil and the substrate, the substrate will be cooled before it leaves barometric leg 40. This oil can also serve as a protective coating for the aluminum coated black iron or the oil may be replaced by a different type of oil in the barometric leg 46 if such a different type of oil is desired. Obviously the requisite oil levels will be maintained in the two barometric legs by suitable additions of oil thereto.

A plurality of vacuum pumps are preferably provided for maintaining the trap chamber at the lowest pressure in the system. This may be accomplished, for example, by providing a large high vacuum pump 52 (e.g. a mechanical blower or diffusion pump) which evacuates the coating chamber 12 by pumping out the trap chamber 36 and permitting any gases generated in chamber 12 (or leaking into chamber 12) to travel through the passage 34 into the trap chamber 36 where they are pumped out by the pump 52. Suitable other vacuum pumps 54, 56, 58 and 60 are provided for evacuating chambers 44, 20, 18 and 16, respectively, to the total pressures indicated for these various chambers.

In one preferred embodiment of the invention, the first chamber 16 is maintained at about 100 mm. Hg abs., the second chamber 18 is maintained at about 1 mm. Hg abs., the third chamber 20 is maintained at about 50 microns Hg abs. and the coating chamber 12 is maintained at about 1 micron Hg abs. The trap chamber 36 is maintained at about .5 micron Hg abs., and the cooling coil is operated at a temperature on the order of 5° C. to 10° C. This temperature is adequate to maintain the vapor pressure of a commercial, mechanical pump oil 40 at less than .5 micron Hg abs. As mentioned, the oil 40 is preferably a commercially available mechanical pump oil which can conveniently be a straight chain paraffin oil which has been treated to remove low boiling fractions. The oil 46 in the second barometric leg can be the same as the oil in the first barometric leg 40 or can be a different oil depending upon the desired operating conditions. Equally, it can be another liquid such as water or the like, although an oil is preferred for the protection of the coated substrate.

The passage 34 through which the freshly-coated substrate passes from the coating chamber 12 to the trap chamber 36 is preferably many times thicker than the substrate so that there will be no danger of scratching the freshly-deposited aluminum coating. It is desired that this passage 34 have a length along the travel of the substrate which is appreciably greater than the mean free path of residual gas molecules at the pressure of the system. This mean free path at 1 micron is about 2½ inches. With this construction, random diffusion of the vapors from trap chamber 36 into the coating chamber 12 will not take place to any appreciable extent. When the chamber 36 is maintained at a lower pressure than the coating chamber 12, there is a net flow of vapors

from the coating chamber 12 to the trap chamber 36. If desired, the passage 34 can have a height of several inches and can contain a number of plastic sheets extending generally transverse to the substrate in position to cut down random diffusion vapors from the chamber 36 to the chamber 12. In such case, it is preferred that the plastic sheets contact the freshly-coated aluminum surface only very lightly, if at all.

Numerous modifications of the invention may be made from the specific forms schematically illustrated and described above. For example, the coating chamber 12 may be provided with high vacuum pumps so as to maintain a pressure on the order of 1 micron, and if desired, a slight leak of air or other gas can be provided to maintain the slight excess of pressure in the coating chamber 12 over the pressure in the trap chamber 36. The sheet material can be coated on both sides by providing a second source in the second chamber and passing the upper side of the substrate over the second source.

Since certain changes may be made in the above apparatus without departing from the scope of the invention herein involved, it is intended that all matter contained in the above description or shown in the accompanying drawings be interpreted as illustrative and not in a limiting sense.

What is claimed is:

1. Apparatus for coating a metallic substrate with another metal which comprises a high-vacuum coating chamber, means for maintaining the coating chamber at a pressure below about 10 microns Hg abs., means for passing the substrate into the coating chamber from the atmosphere, and means for removing the coated substrate from the coating chamber to the atmosphere, said removing means including a liquid barometric seal, a trap chamber between the coating chamber and the barometric seal, and means for maintaining the trap chamber at an absolute pressure less than that of the coating chamber.

2. Apparatus for coating a metallic substrate with another metal which comprises a high-vacuum coating chamber, means for maintaining the coating chamber at a pressure below about 10 microns Hg abs., means for passing the substrate into the coating chamber from the atmosphere, and means for removing the coated substrate from the coating chamber to the atmosphere, said removing means including a barometric seal, a trap chamber through which the substrate passes between the coating chamber and the barometric seal, and means for maintaining the trap chamber at an absolute pressure less than that of the coating chamber, said barometric seal comprising a liquid having a vapor pressure of 1 micron Hg abs. at a predetermined temperature, means for maintaining said liquid below said predetermined temperature despite addition of heat thereto by hot substrate passing into said liquid, and means positioned between said coating chamber and said barometric seal for condensing vapors of said liquid at a temperature below said predetermined temperature.

3. The apparatus of claim 2 wherein said trap chamber and said coating chamber are connected by means of a passage having a thickness many times greater than the thickness of the substrate, said passage constituting the principal passage for vapors between said two chambers and said means for maintaining a lower pressure in said trap chamber providing a flow of vapors through said passage from the coating chamber to the trap chamber.

4. The process of coating a metallic substrate with another metal which comprises the steps of passing the substrate into a vacuum chamber maintained at a pressure below about 10 microns Hg abs., heating the substrate during its passage into said chamber, providing a stream of vapors of said other metal in said vacuum chamber, passing said metallic substrate through said stream of metal vapors, condensing vapors of said other metal on

the hot substrate, passing the thus coated substrate into a second chamber, maintaining the second chamber at a pressure lower than the pressure in the coating chamber, immersing the hot coated substrate in a liquid bath in the second chamber to cool the substrate, condensing vapors of the liquid bath immediately adjacent the surface thereof, and passing the substrate through a barometric seal comprising said liquid.
